UNITED STATES PATENT OFFICE.

NEWLAND MOULTON, OF MERRIMAC, MASSACHUSETTS.

PROCESS OF MAKING FELT UPPERS FOR SHOES OR SLIPPERS.

SPECIFICATION forming part of Letters Patent No. 275,249, dated April 3, 1883.

Application filed August 7, 1882. (No model.)

To all whom it may concern:

Be it known that I, NEWLAND MOULTON, of Merrimac, in the county of Essex, State of Massachusetts, have invented a certain new 5 useful Improvement in the Process of Making Felt Uppers for Shoes or Slippers, of which the following is a description sufficiently full, clear, and exact to enable any person skilled in the art or science to which said invention 10 appertains to make and use the same, reference being had to the accompanying drawings, forming part of this specification, in which—

Figure 1 is a plan view of the cone used in this process; Fig. 2, the two blanks after they 15 are cut and removed from the cone; Fig. 3, one of the blanks after it has been hardened, felted, reduced in size, and forming the upper, ready for lasting.

This invention relates to an improvement for 20 forming open-bottom seamless felt uppers for shoes and slippers.

The invention consists in the process hereinafter set forth.

In carrying out this process the cone shown 25 in Fig. 1 is used. This cone is made cylindrical, with the curved or conical ends somewhat like the cone used in hatting, except that it is shorter in proportion to its diameter. This cone is placed upon the former just as the cones 30 in ordinary hat-forming are, and the web as it comes from the cards is carried completely around and over the said cone and wound about

itself to the thickness required. The web thus wound and shaped about the cone is then cut along the diagonal line x x , Fig. 1, the usual groove, a , allowing the use of shears, forming blanks B B. These blanks are then hardened and felted by the usual process used in hatting, and which needs no special description, and are dried and surfaced as usual. Along 35 the line y y a cut is made for the ankle-hole. This cut may be made before or after they are 40 lasted.

This process produces the open-bottom seam- 45 less upper shown in Fig. 3, which is the object and aim of the invention. No claim is herein made for this article, as it is the subject of another patent. This upper is to be secured to a sole forming a completed slipper or shoe in any proposed way.

Having described my invention, what I claim 50 is—

The process herein described for forming 55 seamless open-bottom felt uppers, which consists in the following steps: winding the web about the cone, cutting it, thus wound, on the diagonal line x x , thus forming the blanks for two distinct uppers, hardening the blank thus formed, and felting it, all substantially as herein set forth.

NEWLAND MOULTON.
